UNITED STATES PATENT OFFICE.

GEORGE R. CORNWALL, OF RYE, NEW YORK, ASSIGNOR, BY MESNE ASSIGNMENTS, TO
JAMES G. COFFIN, TRUSTEE.

PLANOGRAPHIC-PRINTING APPARATUS.

1,127,736.

Specification of Letters Patent.

Patented Feb. 9, 1915.

Continuation in part of application Serial No. 172,317, filed September 8, 1903. This application filed October 6, 1904, Serial No. 227,509. Renewed May 4, 1911. Serial No. 625,086.

To all whom it may concern:

Be it known that I, GEORGE R. CORNWALL, a citizen of the United States, and residing at Rye, Westchester county, in the State 5 of New York, have invented certain new and useful Improvements in Planographic-Printing Apparatus.

The following is a description and specification of my invention and of the manner 10 of constructing and using the same to enable those skilled in the art to understand and use my invention.

My invention relates to apparatus for use in connection with planographic printing 15 and a planographic surface consisting of line bars or units each of which is adapted to receive a line of the composition. A planographic surface of this character is described in Letters Patent of the United 20 States No. 753,368, granted to me.

My present invention also relates to means for assembling and holding the line bars or units in accurate position to receive the lines of impressions from a transfer sheet and 25 means for insuring with rapidity and certainty the accurate registry of each line of the composition with a separate line bar or unit.

My invention further relates to means for 30 obtaining a proof impression from the line bars or units, means for correcting the proof and producing a corrected impression by the transposition, rearrangement or elimination of bars, or the insertion or addition 35 of other bars.

The object of my invention is to provide a means or apparatus for assembling and holding line bars or units in accurate position so that a single bar will receive a single 40 line of composition and to provide bars to coöperate with said assembling and holding means for the purpose described.

A further object of my invention is to provide means whereby a proof impression 45 may be taken from said bars with means for changing the arrangement or order of the bars, the insertion or addition of new bars, the variation of the leading or line spacing and to provide means for protecting the as-

sembling and holding means during the 50 making of the proof impression.

Other objects will appear in the following description and claims.

I have illustrated my invention in the accompanying drawings, in which—

55

Figure 1 represents a plan view of the assembling and holding means, parts being shown by dotted lines and other parts broken away to illustrate the construction. This view shows the assembling means 60 locked to hold the bars. Fig. 2 is a transverse sectional view, line A—A, Fig. 1. Fig. 3 is a partial view of Fig. 1 showing the assembling and holding means unlocked. Fig. 4 is a sectional detail view on line 65 B—B, Fig. 1. Fig. 5 is a sectional detail view on the line C—C, Fig. 1 looking in the direction of the arrow. Figs. 6 and 7 are detail sectional views showing the operation of the detents for the registering strips 17. 70 Fig. 8 illustrates one form of line bar or unit. Figs. 9 and 10 are broken views illustrating the employment of bars of different widths or thicknesses. Figs. 12, 13, 15, 16 and 18 are similar views of modifications 75 of the form of the bars. Figs. 11, 14, 17 and 19 are detail perspective views showing different forms of bars. Figs. 20 and 21 are broken views of a transfer sheet showing 80 registering means thereon. Fig. 22 is a partial view of the assembling and holding means for use with a transfer sheet of the character shown in Fig. 21. Figs. 23 and 24 are views showing protecting plates employed in carrying out the invention. Fig. 85 25 is a sectional detail view illustrating a portion of the plate shown in Figs. 23 and 24. Figs. 26 and 27 show assembling and holding means for the bars or line units when taking an impression therefrom; Fig. 90 27 showing an improved form for this purpose, and Fig. 26, the line bars with the justified lines of characters transferred thereto from the transfer sheet. Figs. 28 and 29 are transverse sectional views on 95 lines E—E and D—D, Figs. 26 and 27 respectively. Fig. 30 is a longitudinal sectional view on line F—F, Fig. 27. Fig. 31

illustrates a locking and retaining bar for use in connection with the assembling and holding means, shown in Fig. 27. Fig. 32 is a broken view of another form of transfer sheet.

The present invention is in the nature of an improvement on that set forth in my application for United States Letters Patent No. 172,317, filed September 8, 1903.

10 In carrying out the present invention, I provide a chase or frame which may be conveniently formed of three integral sides 1 and a separate side 2. The integral portion constitutes one side and two ends and the 15 separate portion 2, constitutes the other side. The side 2 is secured to the other portion 1 by means of screws 3—3 tapped into threaded sockets 4—4; dowel pins 5—5 are provided to accurately position the side 2.

20 Along the inner sides of the frame or chase so formed are arranged notched strips 6—6^a, having notches 7 to receive the ends of the bars B. The strip 6 is secured to the portion 1 of chase by means of screws 6^b—6^b.

25 The notched strip 6^a is loosely mounted in the other side of the chase guided upon pins 8—8 in the inner edge of the strip 2. The notched strip 6^a has spring connections with the side 2 by means of tension springs 9—9 which are received in openings or housings 30 10—10 in the side 2. One end of each of these springs is secured to the strip 6^a, their other ends being secured to screw plugs or caps 9^a. The action of these springs, as will 35 be seen, is to withdraw the strip 6^a away from the ends of the bars. The strip 6^a is moved inwardly toward the ends of the bars to clamp the same in position by means of cams 11—11 pivotally mounted at 12—12 in 40 the side 2. These cams are caused to work in unison by means of a link 13 which connects them together. One of the cams is formed with a handle or lever 14 by means of which the cams are operated. A spring 45 latch 15 is mounted near the corner of the chase adjacent lever 14 to hold the chase in locked or clamped position. A stop 15^a is provided to limit the throw of lever 14.

In the two longitudinal sides of the chase 50 are mounted bars or strips 17 provided in their upper faces with teeth or pins 18. said strips 17 being received in longitudinal channels or grooves 16. The teeth or pins 18 in said strips are so arranged as to register in line with the bars B, each pin being opposite the end of a bar, and preferably in line with its longitudinal center. These pins form positioning or locating means for the lines of composition to be transferred to 55 the bars—the transfer sheet being provided with perforations which bear the same relation to the lines of composition to be transferred to the bars as these pins 18 bear to the bars. Strips 17 are supported in their 60 grooves 16 upon springs 22—22 which tend

to force said strips upwardly, as shown in Fig. 5. In the ends of said strips are slots 19 through which pass pins 20 having screw parts 21 by which they are secured in the sides of the chase, said slots being of proper length to limit the movement of the strips. Near the ends of said strips on their outer side are formed steps 24, 25 in position to be engaged by the ends of spring bolts 26, said bolts being suitably mounted in the side portions of the chase and having springs 27 tending to press said bolts inwardly to engage said steps 24—25. The ends of said bolts are formed with knurled portions 28 to form secure finger holds. The action of the 70 bolts and the steps is to hold the strips 17 in depressed positions as illustrated in Figs. 6 and 7, for a purpose hereinafter described. A longitudinal bar 30 is detachably arranged across the opening in the chase to prevent the bars from falling through when the chase is lifted or carried, the bars being formed with a notch or cut 39 in their rear faces to receive said bar, it being understood that said notch fits loosely over the bar as 75 clearly shown in the sectional view, Fig. 2.

I may employ various forms of bars B and notches 7, it being understood that the bars B are so formed as to coöperate with the notches to be accurately positioned with 80 relation to the pins 18 or equivalent registering means, when the lever 14 is operated. To this end I provide notches and bars of such a form that the bars will automatically 85 find their notches when the chase is locked being guided therein by the shape of the notches and of the ends of the bars. In Fig. 8 I have shown a form of bar for coöperating with the form of notch shown in Fig. 1, the bar being provided with beveled or 90 tapering faces 31. Other forms of bars may be employed for this purpose as shown for instance in Figs. 9—10, in which the edge of the bar formed by the meeting of beveled faces 31 is chamfered or truncated to form 95 flat ends 33, see Fig. 11. In Figs. 12, 13 and 14 is shown another form of bar and notch in which the ends and faces are tapered or beveled and in which is provided a shoulder 100 or abutment 34. In Figs. 15, 16 and 17 is 105 shown another form of bar and notch, the end of the bar being formed with a tongue 35 inserted therein to coöperate with the form of notch shown in Figs. 15 and 16, the corners of the notches and the tongue being 110 beveled or chamfered as shown. Still another form of notch and bar is shown in Figs. 18 and 19, the notch being formed by small tongues or projections 38 let into the side 115 pieces 6—6^a and receiving between them the 120 ends of the bar shown in Fig. 19, the corners of the tongues or projections 38 and also the 125 corners of the bar being chamfered as indicated by the numeral 37, Figs. 18 and 19.

With the form of chase herein illustrated 130

and described bars of different widths may be used as is shown in Figs. 9 and 10, Fig. 10 showing a narrower bar than Fig. 9, see also and compare Figs. 12, and 13 and Figs. 15 and 16. This is for the purpose of accommodating different type sizes, for instance, 6 point, 7 point, 8 point, etc.

It will be understood that the transfer is made from a transfer sheet, such for instance as is shown in Fig. 20, the matter being in the case of letter press usually in justified lines as appears clearly from Fig. 26 of the drawings, upon the bars after they are locked in position in the chase. In order to accurately register the lines of composition on the transfer sheet with the bars, said sheet is provided with positioning or locating marks bearing the same relation to the lines of composition as the pins 18 bear to the bars. In Fig. 20 I have shown a sheet provided with these marks in the form of perforations 50. When the transfer is made the perforations 50 are placed over the pins 18 and thus the lines of impression are accurately placed each upon a separate bar. These perforations 50 may either be perforations specially made for this purpose either before or during the impression of the composition upon the transfer sheet; or perforations 50^a which represent the sprocket feed perforations, such as are employed in automatic typographic apparatus in which the composition is impressed upon the transfer sheet said sheet being fed by means of the holes 50^a, a line space at a time, see Fig. 32.

Instead of perforations, the positioning or locating means may be in the form of marks such as cross marks 51—52, shown in Fig. 21 which are printed or otherwise formed on the back of the transfer sheet while the same is receiving the composition. When this character of locating or position means is employed the strips 17 and pins 18 are dispensed with and the face of the chase is marked with cross marks 53—54, as shown in Fig. 22, corresponding to marks 51, 52 which bear the same relation to the bars as marks 51 and 52 bear to lines of composition.

When the transfer is to be made to the bars, they are securely locked in the chase, by means of the locking means described.

In order to protect the notches or recesses 7 and working parts of the chase, such as the strips 17 and the movable side 2 with its cams, etc., during the process of making the transfer, I provide a plate 47, shown in Fig. 23, of the same form and size as the chase with a central opening 48 to expose the bars B therethrough. This plate 47 is made of the same material as the bars so as to present the uniform character of surface therewith. In the plate 47 are arranged openings 49 to receive the strips 17 which project upwardly therethrough, the pins or teeth 18 projecting above the surface of the plate 47.

The bars B are formed of a slightly greater height than the chase, as clearly shown in Fig. 2 and are provided with shoulders 32—32 see Figs. 8, 11, 14 and 17, so that the portions of the bars which project above the surface of the chase are rectangular and closely fit against the sides of the openings 48 of the plate 47 when the same is placed on the chase. The thickness of plate 47 is equal to the depth of the shoulder 32 so that when the plate 47 is placed in position, the surface of the bars is in the same plane as the upper surface of plate 47.

Fig. 25, a, shows the relative position of plate 47 in place, with the teeth 18 projecting above the surface of the plate. The transfer sheet may now be applied and positioned by means of the locating marks or perforations. In making the transfer, the transfer sheet is pressed closely in contact with the bars. The presser passing over the teeth 18 in strips 17 depresses said strips until they are caught or held in depressed position by the spring bolts 26 engaging the first step 25, see Fig. 7. Plate 47 may now be removed, after cutting the transfer sheet around the opening 48; and plate 55, see Fig. 24, is then placed upon the chase and over the bars; this plate being provided with a similar opening 45 through which the surface of the bars appear. Plate 55 is of the same material as the bars themselves and forms therewith a uniform planographic surface. This plate 55 has no opening to receive the strip 17, these strips being covered or protected by the plate so that the water, gum, acids and other fluids and materials employed in making the transfer to the bars and in fixing the impressions thereon are prevented from finding their way into any portions of the chase where they might do injury by causing corrosion and preventing the working of the parts. When this plate 55 is placed on the chase over the bars it depresses strips 17 which are immediately caught and held in depressed position by bolts 26 engaging notches 25, see Figs. 6 and 25, b. Plates 47 and 55 are provided with pins 55' to register with holes 1^a in the chase so that said plates may be rapidly and accurately positioned.

An important feature of advantage possessed by my invention consists in the arrangement of the notches 7 which receive the ends of the bars at such a distance apart that spaces S are left between adjacent bars. These spaces serve an important purpose, viz: They permit the fluids and other materials used in transferring and rolling up the design on the bars to escape. Where the bars are brought close together when a design is being transferred thereon, the water and other fluids and materials used to roll up the design or to bring the surface into condition to receive and hold the transfer

find their way into the interstices or joints between the bars and will in the treatment of the bars and rolling up of the design subsequently ooze up again on to the surface 5 and spread over the same and over the design or impressions thereon and prevent them from properly taking ink, thus causing imperfect and partly obliterated impressions. With spaces S between the bars there 10 is no tendency for this defect and imperfection to occur. The fluids, etc., find free escape from between the bars and what slight film may remain on the sides of the bars will rapidly evaporate or may be removed by wiping if desired. Thus perfect 15 impressions are insured.

The chase above described is employed for the transfer of the composition or design to the bars. After the composition or design 20 has been fixed upon the bars, a proof impression may be taken, which proof may be read and corrected and any desired alterations may be made in accordance with the corrected proof by removing bars and substituting other bars in their place with the 25 corrected matter thereon; or the bars may be transposed or rearranged in accordance with the corrected proof; or additional bars added. The chase is then unlocked and strip 30 30 is removed by taking out screws 30^a—30^a and the bars in their proper order are, in accordance with the corrected proof, arranged in a chase 40, see Fig. 26, of ordinary form and construction and without the 35 notches for positioning the bars. The bars are secured in this chase by the ordinary wedges or quoins 41 being alined in column by their ends. The leading or line spacing of the composition may be varied in this 40 chase as desired and as shown in Fig. 26 by the insertion of leads between the bars. The upper bars shown in said figure are arranged to give double leading; the bars in the middle portion of said figure are shown arranged 45 to give single leading and the bars in the lower portion are shown arranged to give what is termed solid matter.

Instead of the chase shown in Fig. 26, I prefer to employ a chase of the character 50 shown in Figs. 27, 29 and 30 in which the bars are alined in column alinement by means of a strip 42, see Fig. 31, having beveled portions 43, 44 for engaging similarly under-cut portions 45, 45 in said chase. This 55 bar 42 is of a width along its intermediate portion to fit accurately the cuts 39 in the lower faces of the bars B, as clearly shown in Fig. 29. Thus the bars B are alined in column position by means of said strip 42. An end wedge 41 is employed to securely 60 hold the bars in the chase. From the bars as arranged in this chase a retransfer is taken which is then laid down upon a planographic printing plate of the ordinary and

well known construction, such as a flexible 65 metallic plate which may be secured in well known manner on the form cylinder of an ordinary rotary press and as many impressions taken therefrom as may be required.

In taking the retransfer from the chase, 70 shown in Fig. 27, a plate 55 is employed to form a uniform and level planographic surface with the bars as described in connection with the chase shown in Figs. 1 and 2. This plate protects the ends of the bars from the 75 fluids, etc., employed in making the retransfer, as clearly shown in Fig. 30.

Having thus described my invention the following is what I claim as new therein and desire to secure by Letters Patent:— 80

1. A chase for line bars provided with means for automatically guiding and positioning said bars into line registry with the lines of typographic composition.

2. A chase having means thereon for registering and positioning lines of typographic composition, and means for guiding and positioning line bars into line relation with said registering and positioning means. 85

3. A chase or frame for receiving line 90 units of a composition, said chase provided with positioning means coöperating with the ends of the line units for positioning said units in alinement with the lines of a typographic composition. 95

4. A chase or frame for receiving line units of a composition, said chase provided with a series of means along its inner edges for positioning and retaining said line units in alinement with the lines of the typographic composition. 100

5. A chase or frame for receiving line units of a composition, said chase provided upon its inner edges with a series of notches or recesses for engaging the ends of said line 105 units, said notches bearing definite relation with the lines of the typographic composition.

6. The herein-described means for holding and positioning line units, said means consisting of a chase or frame provided with a series of notches or recesses, means formed on the line units coöperating with said notches or recesses, said notches or recesses spaced apart a distance to position the 115 line units with intervening spaces between adjacent units, for the purpose described. 110

7. The herein-described means for positioning and holding line units, said means consisting of a chase or frame provided with a series of notches, said notches formed with guiding faces coöperating with guiding faces formed on the ends of the line units, and holding and positioning devices for a transfer sheet, said sheet-positioning and 120 holding devices bearing a definite relation with the lines of impressions upon the transfer sheet and with the line units. 125

8. The herein-described means for positioning and holding line units, said means consisting of a chase or frame provided with a series of notches, said notches formed with 5 guiding faces coöperating with guiding faces formed on the ends of the line units, and registering means for the transfer sheet, said registering means bearing a definite relation with the lines of impressions upon the 10 transfer sheet and with the line units.

9. The herein-described means for positioning lines of impressions upon line units, said means consisting of a chase or frame provided with positioning notches or recesses 15 and line bars having their ends formed to engage said notches or recesses, marks on the rear face of the transfer sheet, and registering means corresponding thereto upon the chase or frame, said registering 20 means on the chase bearing a definite relation to the positioning notches and to the lines of impressions upon the transfer sheet.

10. An apparatus of the character described, comprising a chase for line bars, 25 said chase having means for positioning lines of typographic composition, and means bearing a definite relation therewith for holding and positioning the line bars, and line bars formed to coöperate with said holding 30 and positioning means, whereby said bars may be accurately guided and held in definite relation with said line positioning means.

11. An apparatus of the character described, comprising a chase having means 35 for holding and positioning a sheet bearing lines of typographic impressions, said means bearing a definite relation with said lines of impressions, means for guiding and holding 40 line bars, said bar-holding and guiding means bearing a definite line relation with the first named positioning means, and line bars formed to coöperate with said bar guiding 45 and positioning means, and means to clamp the bars in position.

12. In an apparatus of the character described, means for positioning lines of typographic impressions, strips formed with notches or recesses bearing definite relation 50 with said positioning means, and line bars formed to engage said notches or recesses, and means to clamp the bars between the strips.

13. In an apparatus of the character described, means for positioning lines of typographic impressions, a series of notches bearing 55 definite line relation with said positioning means, and line bars formed to engage said notches or recesses whereby said bars 60 are held in definite line relation with said positioning means, the bars and notches coöperating to hold the bars at a distance apart one from the other, and means to clamp or hold the bars in position.

14. In an apparatus of the character de- 65 scribed, means for positioning lines of typographic impressions, a member having a series of notches bearing fixed and definite relation to the positioning means, said notches being formed with guiding surfaces 70 thereon, line bars having their ends formed with coöperating guiding surfaces thereon, and means to seat and hold the bars in the notches or recesses.

15. In an apparatus of the character de- 75 scribed, a chase for holding the line bars, means on the chase for positioning lines of typographic impressions, recesses or notches bearing definite line relation with the positioning means, said notches formed with inclined surfaces, and line bars having their 80 ends formed with inclined surfaces to coöperate with the notches, said notches spaced to position the bars a distance apart, one from the other for the purpose described, 85 and means to clamp the bars in position.

16. In an apparatus of the character described, means for positioning lines of typographic composition, said means comprising resiliently mounted teeth bearing definite relation to the lines of impression, notches or recesses for holding line bars, said notches or recesses bearing definite line relation with said teeth, line bars formed to engage said 90 notches, and means to clamp said bars in 95 position, the teeth projecting normally above the face of the line bars.

17. An apparatus of the character described, comprising a chase, or frame, a 100 pair of notched or recessed strips therein, one of said strips movable toward and from the other, cams for operating the movable strip, and a hand lever for operating said cams in unison, and means on the chase for positioning lines of typographic impressions, said means bearing a definite line arrangement with the notches in the strips. 105

18. In an apparatus of the character described, a chase having recesses along the lateral inner sides thereof, line bars having 110 their ends formed with inclined surfaces to coöperate with said notches and position the bars, said bars being of greater height than the height of the chase, a pair of laterally extending resiliently mounted strips, 115 teeth or pins in said strips bearing definite relation with the notches, said teeth or pins normally projecting above the surfaces of the bar, and a plate provided with openings to receive the bars and the strips, said plate 120 of a thickness substantially equal to the difference in height between the bars and the chase, for the purpose described.

19. An apparatus of the character described, comprising a chase or frame, means 125 along the lateral inner edges of the chase for positioning line bars, resiliently mounted strips having teeth or pins bearing defi-

nite relation with the bar positioning means, there being steps or shoulders along the edges of said strips, and spring mounted retaining bolts for engaging said steps or shoulders, for the purpose described.

20. An apparatus of the character described, comprising a chase or frame, having notches along the inner sides thereof for holding and positioning line bars, means to clamp said line bars in said notches, resiliently mounted teeth or pins bearing definite relation with said notches, the chase being of less height than the line bars, and a cover plate for covering the teeth, notches and the ends of the bars, said cover plate being of thickness equal to the difference in height between the chase and the bar.

21. The combination with means for holding a planographic line bar of devices for 20 positioning an inked line of characters with respect to said holder, and means mounted upon said holder for positioning a line bar so that the inked line of characters may impress the bar when brought into impression contact therewith.

22. The combination with a line bar of means for impressing a line of characters thereon and means in definite relation to said impressing means which engage the 30 line bar to position it relatively thereto.

23. The combination with a line bar of means for positioning an inked line of characters and means in definite relation with said first mentioned means for engaging and 35 positioning the line bar to receive the inked line of characters.

24. A device for transferring lines of characters to a printing surface composed of line bars, said device comprising a transfer sheet bearing the lines of characters and having registering means which bear a definite relation to the lines of characters and to the bars constituting the printing surface.

45. 25. A device for transferring lines of characters to a planographic printing surface composed of line bars, said device comprising a transfer sheet bearing the lines of characters and having registering means 50 which bear a definite relation to each line of characters and to the bars constituting the printing surface.

26. A device for transferring lines of characters to a printing surface composed of line bars, said device comprising a transfer sheet bearing justified lines of characters and having registering means which bear a definite relation to each end of the lines of characters and to the bars constituting the 60 printing surface.

27. A device for transferring lines of impressions upon a planographic printing surface composed of line bars, said device comprising a transfer sheet bearing the 65 lines of impression and having holes there-

in which bear a definite relation to each line of impression and to the bars constituting the printing surface.

28. A device for positioning lines of printed characters upon a printing surface 70 composed of a plurality of bars, said device comprising a transfer sheet bearing the lines of characters and having a series of holes bearing a definite relation to the lines of characters and to the bars of the printing 75 surface.

29. A device for positioning lines of printed characters upon a printing surface composed of a series of bars massed together, said device comprising a transfer 80 sheet bearing the lines of characters and having a series of holes arranged opposite the ends of the lines of characters and bearing a definite relation to the lines of characters and to the bars of the printing 85 surface.

30. A device for positioning lines of printed characters upon a printing surface composed of a plurality of bars, said device comprising a transfer sheet bearing the 90 lines of characters and having a series of holes arranged opposite the ends of the lines of characters bearing definite relation to the lines of characters and to the bars of the printing surface.

95 31. A device for positioning a line or lines of impressions upon a printing surface made up of one or more planographic line bars, said device comprising means to position the line or lines of impressions in 100 definite relation to the bar or bars.

32. A device for positioning a line or lines of impressions upon a printing surface made up of one or more line bars, said device comprising a chase or frame 105 for holding said bar or bars, said chase provided with means for holding said bar or bars in definite relation to the line or lines of impressions.

33. A device for positioning a line or 110 lines of impressions upon a printing surface made up of one or more line bars, said device comprising a chase or frame for holding said bars, said chase provided with registering means bearing a definite relation 115 to the respective bars and to the respective lines of impressions.

34. An apparatus of the character described comprising a chase for holding one or a plurality of line bars, a transfer sheet 120 bearing lines of impressions, registering means on said sheet bearing definite relation to the lines of impressions, positioning means on the chase for said sheet to co-operate with the registering means on the 125 sheet, and means to hold said line bars in definite relation to the positioning means on the chase.

35. An apparatus of the character described comprising a chase or frame having 130

means for holding a series of line bars, said line bars constituting a planographic surface, a transfer sheet bearing lines of impressions and having registering means

5 thereon bearing definite relation to said lines of impressions, a series of projections on the chase for engagement with the registering means on the sheet, said projections bearing a relation to the bars similar to the relation
10 which the registering means on the sheet bears to the lines of composition.

36. An apparatus of the character described comprising a chase or frame for holding a plurality of line bars, said bars
15 constituting a planographic printing surface, resiliently mounted projections on said chase bearing definite relation to the line bars, a transfer sheet bearing lines of impressions to be transferred to the bars, said sheet having registering means adapted to coöperate with said projections, said registering means bearing the same relation to the lines of impressions as said projections bear to the line bars.

25 37. The herein-described means for positioning and holding lines of printed characters upon a planographic printing surface composed of a plurality of bars, said means comprising a transfer sheet bearing the
30 lines of characters, holes in the sheet bearing a definite relation to the lines of characters, and a chase or frame for holding the printing surface, said frame having projections bearing a definite relation to the bars
35 of the printing surface and arranged to engage the holes of the transfer sheet.

38. The combination with means for positioning a planographic line bar and an inked line of characters with reference to each
40 other, of means for bringing the line of characters and the line bar into impression contact so that the line of characters will be impressed upon the line bar.

39. The combination with means for positioning a planographic line bar and an inked
45

line of characters relatively to each other, of means for impressing the line of characters upon the line bar.

40. The combination with a planographic line bar, of means for holding said bar, and
50 registering means carried by said holding means and having a definite relation to the said bar.

41. The combination with a planographic line bar, of holding means for said bar,
55 registering means carried by said holding means near each end of said bar and in definite relation thereto.

42. The combination of means for supporting a planographic line bar, of means
60 for locating and impressing a line of characters upon said bar.

43. The combination of means for supporting a planographic line bar, of means
65 for locating and impressing a line of inked characters upon said bar.

44. The combination with a planographic line bar of a support therefor having registering means adapted to coöperate with each end of said bar and bearing a definite
70 relation thereto.

45. The combination with a planographic line bar of a support therefor having registering means adapted to coöperate with each end of said bar and bearing a definite relation thereto, and means coöoperating with
75 said registering means to impress the line of characters in a definite location.

46. The combination with a planographic line bar of a support therefor having registering means adapted to coöperate with each end of said bar and bearing a definite relation thereto, and means coöoperating with
80 said registering means to impress the line of inked characters in a definite location.

85 GEORGE R. CORNWALL.
